UNITED STATES PATENT OFFICE.

FREDERICK GEORGE FRYER, OF YORK, ENGLAND.

REDUCING OR REFINING APPARATUS FOR CHOCOLATE, COCOA, AND THE LIKE.

Application filed July 19, 1926. Serial No. 123,471.

This invention relates to reducing, grinding or refining apparatus for chocolate, cocoa and the like, particularly of the kind comprising relatively rotatable reducing discs of metal, the operative faces of which are pressed together into a single plane under yielding pressure and are suitably formed to reduce the cocoa liquor, for example, in its passage from centre to periphery of the disc.

The present invention has in view obtaining a gradually changing area of reducing surface in successive elemental annular disc areas throughout the operative portion of the disc.

To this end, according to the present invention, each disc is provided with reducing walls forming reducing surfaces so arranged that the total area of all those elements of reducing surface which lie in an elemental annular disc-area increases more or less proportionately with the radius of the elemental disc-area.

In the embodiment of the invention hereinafter described, the said total area of reducing surface in an elemental annular disc-area increases with the radius, not exactly proportionately therewith, but at a somewhat greater rate than said radius, since it is preferred that a greater concentration of reducing surface be provided in the region of the outside edge of the reducing disc.

In this embodiment, the aforesaid reducing walls comprise a radial series of more or less circumferential reducing walls, for instance a concentric series of ring-formed walls of zig-zag form, which during operation effect a relatively high degree of restriction to the outward flow of the material being reduced, for instance, effect such a restriction that at times momentary sealing of the material occurs.

In the hereinafter described embodiment of the present invention, each disc is provided with concentric ring-formed reducing walls, or rings, having reducing faces the medial lines of which constitute zig-zag curves, the outer apices of any given curve being at the same radius from the centre of the disc as the inner apices of another curve.

In order to obtain an effective distribution of the reducing surface of the walls on the disc, the inner and outer apical angles of each curve are made substantially equal.

The curves may be either equally spaced

from one another throughout the disc or, as in the preferred hereinafter-described embodiment of the invention, the average spacing of outer pairs of adjacent curves may be less than that of inner pairs. This is obtained by spacing the inner apices of each pair radially further apart than its outer apices.

If desired, rows of comparatively narrow reducing pockets may be provided between the ring-formed reducing walls, or such pockets may be dispensed with, so that there would be between adjacent rings merely a ring-formed groove.

One embodiment of the invention is illustrated by way of example in the accompanying drawing, wherein

Fig. 1 is a plan view of a reducing sector provided with zig-zag reducing walls or rings, with a broken-off portion of an adjacent sector, and

Fig. 2 is a section on the line A—A in Fig. 1.

Figs. 3, 4 and 5 are sections on the lines BB, CC and DD, respectively, in Fig. 1.

Fig. 6 is a diagrammatic front elevation of a reducing disc built up of sectors, and

Fig. 7 is a diagrammatic sectional view of the relevant parts of the entire machine.

Referring to the drawings, the sector 1 shown constitutes an element of a reducing or grinding disc 12 (Fig. 6) made up of similar sectors, and the assembled disc contacts with a second disc 10 (Fig. 7) made up of sectors similar to those of the first.

The sectors are castings, only one of the two radial edges of each sector being provided with a radial wall 9. The arrows at the left of Figs. 1, 3, 4, 5 indicate the direction of rotation of the completed disc.

Referring to Fig. 7, a pair of reducing discs 12 are mounted in known manner on a supporting disc 11, which is keyed to the driving shaft 13. The pair of reducing discs 10 are carried by supporting discs 14, 15, of which disc 14 is stationary while disc 15 is slidable on guide-pins 16 secured to the disc 14, and is acted upon by helical compression springs 17, whereby the operative faces of the reducing discs 10, 12 will be pressed together under yielding pressure.

The reducing disc 12 is provided with concentric ring-formed reducing walls 2, fragments of which are shown diagrammatically in Fig. 1. They effect during the operation of the machine a relatively high

degree of restriction to the outward flow of the material being reduced and provide during certain periods a yielding seal to outward movement of material encircled by them. In the present instance however this sealing occurs only momentarily.

The diagrammatic full lines in Fig. 1 indicate the medial lines of the reducing faces of the rings of reducing walls, and constitute zig-zag curves spaced apart, according to the present invention, in such manner that the outer apices (as 21) of any given curve 2 are at the same radius as the inner apices (as 22) of another curve. In the embodiment shown the curve containing the outer apices 21 is the second curve from that containing the inner apices 22, but the curves may alternatively be so designed that the above condition holds for adjacent curves or 20 for a given curve and a curve of an ordinal number greater than the second.

In all the zig-zag curves the inner apical angle (as the angle at the apex 22) is made equal to the outer apical angle (as that at 25 the apex 23) of the same curve. Owing to the above-described arrangement of zig-zag curves the total area of all those elements (as 3, 31, 32) of reducing surface on the zig-zag rings which lie in an elemental annular disc-area (as 5, 51, 52 respectively) increases more or less proportionately with the radius of the elemental annular disc-area.

The curves may be either equally spaced from one another throughout the disc, or, as 35 in the embodiment shown, the average spacing of outer pairs of adjacent curves may be less than that of inner pairs, for example, the spacing of the outer pairs 24 may be less than that of the inner pair 25. To this end, 40 in setting out the curves, the inner apices (as 251) of each pair (as 25) are spaced radially somewhat further apart than its outer apices (as 252).

Between adjacent zig-zag reducing surfaces or walls 2 is provided a row of narrow reducing pockets 7 so that the space between said walls is fully utilized. The pockets are shown of constant width throughout and extend more or less radially from the centre 50 of the disc, and in the present case, slant somewhat in the direction of rotation of the disc 1. The nearly radial intervening reducing surfaces of the walls 71 between the pockets 7 will be substantially equally disposed over the entire operative face of the disc, in other words, the total area of all 55 those elements (as 4, 41, 42) of their reducing surface which lie in an elemental annular area (as 5, 51, 52) will increase more or 60 less proportionately with the radius of the elemental annular disc-area.

As stated above, this condition also holds for the reducing rings 2, so that the total area of all those elements of reducing surfaces 65 which lie in an elemental annular disc-

area, for example, the total area of elements 3, 4, 3 and so on, 31, 41, 31 and so on or 32, 42, 32 and so on, which lie respectively in a disc-area 5, 51, or 52 will increase more or less proportionately with the radius of the 70 elemental annular disc-area.

As already stated, instead of the reducing rings 2 being spaced in the manner shown, they may be equally spaced from one another throughout the disc, in which case the 75 said total area of reducing surface in an elemental annular disc-area will increase substantially exactly proportionately with the said radius, but in the embodiment shown wherein the spacing of an outer pair (as 24) 80 of zig-zag rings is less than that of an inner pair (as 25), the said total area of reducing surface in an elemental annular disc-area increases at a somewhat greater rate than said radius, whereby a greater concentration of 85 reducing surface is provided in the region of the outside edge of the disc.

In the embodiment shown, the pockets 7 vary in depth, the latter decreasing progressively from the most central pockets to the 90 outermost pockets. This will be clear from Figs. 2-5.

At the right or inner portion 8 of the sector shown in Fig. 1 feeding grooves are provided in known manner. Their radial boundary walls may be omitted, if desired.

The rows of narrow reducing pockets 7 may be dispensed with or reduced in number. In the former case the radial walls 9 would be omitted; in the latter, they would 100 reduce the number of pockets in a row to the number of sectors in the disc.

I claim:

1. Reducing or refining apparatus for chocolate, cocoa or the like, comprising a 105 pair of relatively rotatable discs having operative faces pressed together into a single plane under yielding pressure, each disc having a surface made up of elemental annular disc-areas and having reducing walls forming reducing surfaces, the total area of all those elements of said reducing surfaces which lie in an elemental annular disc-area increasing substantially proportionately with the radius of the elemental annular disc-area. 115

2. Reducing or refining apparatus for chocolate, cocoa or the like, comprising a pair of relatively rotatable discs having operative faces pressed together into a single 120 plane under yielding pressure, each disc having a surface made up of elemental annular disc-areas and having reducing walls forming reducing surfaces, the total area of all those elements of said reducing surfaces 125 which lie in an elemental annular disc-area increasing with but at a somewhat greater rate than the radius of the elemental annular disc-area.

3. Reducing or refining apparatus for 130

chocolate, cocoa or the like, comprising a pair of relatively rotatable discs having operative faces pressed together into a single plane under yielding pressure, each disc having a surface made up of elemental annular disc-areas and having a radial series of reducing walls forming reducing surfaces, the total area of all those elements of said reducing surfaces which lie in an elemental 10 annular disc-area increasing substantially proportionately with the radius of the elemental annular disc-area, and the radial series 15 of reducing walls on one disc being substantially coincident with the radial series on the other disc in one relative position of the two discs and substantially out of coincidence therewith in a second relative position.

4. Reducing or refining apparatus for chocolate, cocoa or the like, comprising a pair of relatively rotatable discs having operative faces pressed together into a single plane under yielding pressure, each disc having a surface made up of elemental annular disc-areas and having a radial series of reducing walls forming reducing surfaces, the radial series being of similar form in the two discs, the total area of all those elements of said reducing surfaces which lie in 25 an elemental annular disc-area of either disc increasing substantially proportionately with the radius of the elemental annular disc-area, and the radial series of reducing walls on one disc being substantially coincident with the radial series on the other disc in one relative position of the two discs and substantially out of coincidence therewith in a second relative position.

5. Reducing or refining apparatus for chocolate, cocoa or the like, comprising a pair of relatively rotatable discs having operative faces pressed together into a single plane under yielding pressure, each disc having a surface made up of elemental annular disc-areas and having a radial series of reducing walls with reducing faces forming zig-zag curves, the total area of all those elements of said reducing faces which lie in an elemental annular disc-area increasing 45 substantially proportionately with the radius of the elemental disc-area, and the radial series of reducing walls on one disc being substantially less coincident with the radial series on the other disc in one relative position of the two discs and substantially out of coincidence in a second relative position.

6. Reducing or refining apparatus for chocolate, cocoa or the like, comprising a 60 pair of relatively rotatable discs having operative faces pressed together into a single plane under yielding pressure, each disc having a surface made up of elemental annular disc-areas and having a radial series of ring-formed reducing walls with reducing faces

forming zig-zag curves, the total area of all those elements of said reducing faces which lie in an elemental annular disc-area increasing substantially proportionately with the radius of the elemental disc-area, 70 and the radial series of reducing walls on one disc being substantially coincident with the radial series on the other disc in one relative position of the two discs and substantially out of coincidence in a second 75 relative position.

7. Reducing or refining apparatus for chocolate, cocoa or the like, comprising a pair of relatively rotatable discs having operative faces pressed together into a single 80 plane under yielding pressure, each disc having a surface made up of elemental annular disc-areas and having a concentric series of ring-formed reducing walls with reducing faces forming zig-zag curves, the total area 85 of all those elements of said reducing faces which lie in an elemental annular disc-area increasing substantially proportionately with the radius of the elemental disc area, and the radial series of reducing walls on 90 one disc being substantially coincident with the radial series on the other disc in one relative position of the two discs and substantially out of coincidence in a second relative position.

8. Reducing or refining apparatus for chocolate, cocoa or the like, comprising a pair of relatively rotatable discs having operative faces pressed together into a single plane under yielding pressure, each disc having a surface made up of elemental annular disc-areas and having a radial series of ring-formed reducing walls with reducing faces forming zig-zag curves, the total area of 100 all those elements of said reducing faces which lie in an elemental annular disc-area increasing with but at a somewhat greater rate than the radius of the elemental disc-area, and the radial series of reducing walls on one disc being substantially coincident 110 with the radial series on the other disc in one relative position of the two discs and substantially out of coincidence in a second relative position.

9. Reducing or refining apparatus for chocolate, cocoa or the like, comprising a pair of relatively rotatable discs having operative faces pressed together into a single plane under yielding pressure, each disc having a surface made up of elemental annular disc-areas and having a concentric series of ring-formed reducing walls with reducing faces forming zig-zag curves, the total area of all those elements of said reducing faces which lie in an elemental annular disc-area increasing with but at a somewhat greater rate than the radius of the elemental disc-area, and the radial series of reducing walls on one disc being substantially 120 coincident with the radial series on the other disc in one relative position of the two discs and substantially out of coincidence in a second relative position.

125

130

- other disc in one relative position of the two discs and substantially out of coincidence in a second relative position.
10. Reducing or refining apparatus for 5 chocolate, cocoa or the like, comprising a pair of relatively rotatable discs having operative faces pressed together into a single plane under yielding pressure, each disc having a series of concentric ring-formed reducing walls with reducing faces forming zig-zag curves, the outer apices of any curve being at the same radius as the inner apices of another curve.
11. Reducing or refining apparatus for 15 chocolate, cocoa or the like, comprising a pair of relatively rotatable discs having operative faces pressed together into a single plane under yielding pressure, each disc having a series of concentric ring-formed reducing walls with reducing faces forming zig-zag curves, the outer apices of any curve being at the same radius as the inner apices of another curve externally from this curve.
12. Reducing or refining apparatus for 20 chocolate, cocoa or the like, comprising a pair of relatively rotatable discs having operative faces pressed together into a single plane under yielding pressure, each disc having a series of concentric ring-formed reducing walls with reducing faces forming zig-zag curves, the outer apices of any curve being at the same radius as the inner apices of the second curve externally from this curve.
13. Reducing or refining apparatus for 25 chocolate, cocoa or the like, comprising a pair of relatively rotatable discs having operative faces pressed together into a single plane under yielding pressure, each disc having a series of concentric ring-formed reducing walls with reducing faces forming zig-zag curves, the outer apices of any curve being at the same radius as the inner apices of another curve, and the inner and outer 30 apical angles of each curve being substantially equal.
14. Reducing or refining apparatus for 35 chocolate, cocoa or the like, comprising a pair of relatively rotatable discs having operative faces pressed together into a single plane under yielding pressure, each disc having a radially-spaced series of concentric ring-formed reducing walls with reducing faces forming zig-zag curves, the outer 40 apices of any curve being at the same radius as the inner apices of another curve, and the average spacing of outer pairs of adjacent curves being less than that of inner pairs.
15. A reducing disc, for reducing apparatus for chocolate, cocoa or the like, having a surface made up of elemental annular disc-areas and having reducing walls forming 45 reducing surfaces, the total area of all those elements of said reducing surfaces which lie in an elemental annular disc-area increasing substantially proportionately with the radius of the elemental annular disc-area.
16. A reducing disc, for reducing apparatus for chocolate, cocoa or the like, having a surface made up of elemental annular disc-areas and having reducing walls forming 50 reducing surfaces, the total area of all those elements of said reducing surfaces which lie in an elemental annular disc-area increasing with but at a somewhat greater rate than the radius of the elemental annular disc-area.
17. A reducing disc, for reducing apparatus for chocolate, cocoa or the like, having a series of concentric ring-formed reducing walls with reducing faces forming zig-zag curves, the outer apices of any curve being 55 at the same radius as the inner apices of another curve.
18. A reducing disc, for reducing apparatus for chocolate, cocoa or the like, having a series of concentric ring-formed reducing 60 walls with reducing faces forming zig-zag curves, the outer apices of any curve being at the same radius as the inner apices of the second curve externally from this curve.
19. A reducing disc, for reducing apparatus for chocolate, cocoa or the like, having a series of concentric ring-formed reducing 65 walls with reducing faces forming zig-zag curves, the outer apices of any curve being at the same radius as the inner apices of another curve, and the inner and outer apical angles of each curve being substantially 70 equal.

F. G. FRYER.
